UNITED STATES PATENT OFFICE.

CARL F. LUNDEBERG, OF HARTFORD, CONNECTICUT, ASSIGNOR TO UNDERWOOD TYPEWRITER COMPANY, OF NEW YORK, N. Y., A CORPORATION OF NEW JERSEY.

TYPE-WRITING MACHINE.

No. 853,249.

Specification of Letters Patent.

Patented May 14, 1907.

Application filed November 14, 1906. Serial No. 343,379.

To all whom it may concern:

Be it known that I, CARL F. LUNDEBERG, a citizen of the United States, residing in Hartford, in the county of Hartford and State of Connecticut, have invented certain new and useful Improvements in Type-Writing Machines, of which the following is a specification.

This invention relates to typewriting machines in which, in addition to the usual line-spacing mechanism for the revoluble platen, there is provided an auxiliary mechanism usually at one end of the platen, for feeding a paper ribbon around the platen independently of the latter, or while the platen is stationary. Such strips are employed for the purpose of recording the amounts of successive bills as the latter are written upon the main portion of the platen. During the writing of the bill, the tally-strip remains stationary; and when the bill is completed, the operator copies the amount thereof onto the tally strip, so that the latter at the end of the day may show the total amount of business transacted. When the carriage is moved over far enough to enable the types to write upon the tally strip, auxiliary mechanism is brought into action for line feeding the latter; said auxiliary mechanism being operated by the mechanism of the carriage.

The objects of my invention are to provide improved means for detachably mounting the spool or spool-holder for the paper ribbon, improved means for unwinding the strip from the spool and for pulling the strip from the stationary platen around which it is wrapped, to facilitate the adjustment and manipulation of the paper strip, to provide against premature unwinding of the paper ribbon from the spool during the operation of the machine, to enable the strip carrying portion of the platen to be moved into the printing field when desired without line-spacing the strip, to provide means for regulating the throw of the pawl which feeds the paper ribbon line by line, and to construct the ribbon feeding appliances, so that it may be readily attached to and detached from the paper carriages or platen frames of existing typewriting machines.

Other objects and advantages will herein-after appear.

In the accompanying drawings, Figure 1

is a perspective sectional view to illustrate 55 diagrammatically the course of the paper ribbon in unwinding from the spool and passing around the platen and back therefrom. Fig. 2 is an elevation partly in section taken at the right hand end of the carriage and platen frame of an "Underwood" typewriting machine illustrating my improvements attached thereto.

Fig. 3 is a view similar to Fig. 2, but showing only the moving parts of the mechanism; 65 one of the pressure rolls being released to allow the adjustment of that portion of the paper strip or ribbon which is carried back from the platen. Fig. 4 is a view similar to Fig. 3, but showing the lower pressure roll 70 released. At this figure, the spool-brake is shown cast off, and the line feeding pawl as silenced. Fig. 5 is a rear perspective view of the parts seen at Figs. 3 and 4. Figs. 6 and 7 illustrate the construction of a detachable spool-holder for the paper ribbon. Fig. 8 is a plan showing the usual revoluble platen and its line feeding mechanism as well as the auxiliary ribbon feeding mechanism. Fig. 9 is a rear perspective view of a 80 part of the framework of the machine, and means whereby there is adjustably mounted thereon a cam for effecting the line feeding of the paper ribbon.

My improvements are illustrated in connection with the well known "Underwood" typewriting machine, in which type bars 1 strike against the front side of a platen 2, which is revolubly mounted by means of an axle 3 in a platen frame which comprises end pieces 4 and a connecting rear paper-shelf 5. The platen frame is mounted on a carriage 6, which is drawn along in letter feeding direction by means of a strap 7 and spring barrel 8. Said platen is provided with the usual line spacing mechanism including a ratchet wheel 9, pawl 10, slide 11 and lever 12, all of well known construction in said machine; and pressure rolls 13 guide the wide paper sheets or bills around the platen in the usual manner, said rolls co-operating with a plate 14 curving from the lower portion of the paper-shelf 5 forwardly beneath and up around the front side of the platen. The carriage runs along the usual tracks, one of which is indicated at 15.

The tally strip is coiled at 16 on a spool 17, which is hung just in rear of the tip of the

paper shelf 5, so that the strip may be led forwardly from the spool in between a feeding roll 18, and a roll 19 bearing up against the under side thereof and co-operating therewith to pull the paper or unwind the paper from the spool. From the bite of these rolls, said strip is led forwardly and downwardly to the platen and around the under side thereof, and up in front, so that it may be struck by the types 1. From the platen, it is carried upwardly and backwardly and passed between the feeding roll 18 and a roll 20, which presses down to co-operate with said feeding roll to pull the printed portion of the ribbon from the platen while the latter is stationary. It will be understood that during the usual revolutions of the platen occurring while writing a bill or other document, the rolls 18, 19 and 20 remain stationary, as well as the strip of paper 16; and that the movements of the strip are made while the platen is stationary.

The rolls 18 may be turned by means of a finger piece 21 to run the strip off from the spool and simultaneously pull the leading end of the strip back from the platen at the same speed.

The strip is threaded line by line by means of a ratchet wheel 22 fixed upon the roll 18, and a pawl 23 pivoted at 24 upon an upstanding arm 25 of a slide 26 which is mounted to move forwardly and backwardly upon screws 27; the slide having slots 28 to engage the screws, and the latter being threaded into a plate 29 which co-operates with a companion plate 30 to support the spool and rolls. To said slide 26 is connected the free end of a lever 31 detachably pivoted upon a bracket 32 by means of a screw 33, said bracket fixed to a part of the plate 30. From the free end of said lever depends a pin 34 to engage a cam 35 fixed upon the framework of the machine, so that when the carriage is moved far enough to the left to bring the strip 16 to the printing point, the pin 34 engages the cam 35 and rides thereover, thus vibrating the lever 31 forwardly together with the slide 26 and the pawl 23, to advance the strip feeding roll 18 and the strip thereon.

The top pressure roll 20 is mounted by means of an axle 36 in the arms 37 of a bail which is hinged at 38 upon said side plates 29 and 30 and is pulled down by a spring 39 to press the roll against the feeding roll 18. The bail may be lifted to release the roll 20, since the ends of the axle 36 extend through closed slots 40 formed in the side plates, the latter being confined between said bail arms 37. The pressure rolls 19 and 20 are preferably of soft rubber, and the roll 18 is preferably of hard metal provided with fine longitudinal flutes or milling, as indicated at Fig. 5, whereby perfect control and accurate feeding of the strip is assured. The lower pressure roll 19 is mounted like the roll 20 be-

tween arms 41 of a bail similar to the bail 37, and connected to the lower end of the spring 39; the bail 41 being hinged at 42 upon the side plates 29, 30, and the axle 43 of the roll 19 passing through closed slots 44 in said plates. Thus either roll 19 or 20 may be released while the other remains in engagement with the main feeding roll 18, and hence the strip may be tautened either by pulling back the leading end when only the roll 20 is released, or by pulling back the under portion of the strip when only the roll 19 is released. The rolls may also be released simultaneously if desired; and for convenience in releasing them, the bails may be provided with handles 45, 46.

Overthrow or undue unwinding of the coil from the spool 17 is avoided by the use of a brake in the form of a bail 47 hinged at 48 upon the side plates 29, 30. A draw-spring 49 is connected at one end to a pin 50 upon said bail, and at its other end to a pin 51 whereby to hold the bail lightly against the coil of paper ribbon on the spool. The pin 51 is secured upon a short arm 52 formed upon the pawl 23 and serves to hold the latter in engagement with the ratchet wheel. The bail 47 may be swung up so far that the spring 49 acts upon the other side of bail hinge 48, thereby holding the bail away from the spool, for convenience in tightening the coils on the spool or inserting or removing the spool, or otherwise manipulating the same. The lower pressure roll 19 may be simultaneously cast off, as at Fig. 4, while the top roll 20 remains in use so that by turning the spool 17, the entire paper strip may be drawn taut. It will also be understood that the strip may be, at this time, adjusted relatively to the printing line, that is to say the last line of writing upon the strip may be drawn down to the usual platen scale by simply turning the spool 17, while the parts are in the Fig. 4 position; and to facilitate the adjustment of the strip the top roll 20 may also be released at this time. This renders it very convenient to correct errors on the paper ribbon. It will also be noticed at Fig. 4, that the spring 49 has been caused to swing the pawl 23 out of position to engage the ratchet wheel 22, so that the latter is not rotated by the pawl during the actuation of the latter by the slide 26 and lever 31 when the carriage is run over to the left to bring the paper ribbon 16 into position to be written upon.

The spring 39 also serves to draw the slide 26 rearwardly during the return of the carriage to begin a new line. The spool 17 is detachably mounted upon a spindle or axle 53 having at one end a button 54 and at the other end a tumbler 55 pivoted at 56 upon the end of the axle and having a point 57 to facilitate introduction and passage of the axle through the side plates and the spool. The tumbler when extended is shown in full

lines at Figs. 6 and 7, where it forms a continuation of the axle, having the same cylinder contour; but when the spool rotates, the tumbler gravitates to the dotted line position at Fig. 6, so that one end 58 thereof projects on one side of the axle 53 while the body of the tumbler projects on the other side of said axle, thereby locking the axle against falling out of the machine.

10. The cam 35 is illustrated in the form of a metal plate projecting forwardly from a bar 59 which extends along the carriage and is detachably supported upon the framework of the machine. One end of said bar, Fig. 9, is 15 connected by a screw 60 to an upstanding arm 61 detachably secured by a screw 62 on a part 63 of the framework of the machine. The other end of the bar is attached by a screw 64 to an upstanding arm 65, which is 20 mounted by a hub 66 upon a pivot or gudgeon 67 having a bearing in the opposite portion 68 of the framework, whereby this end of the bar 59 may be swung from the dotted line to the full line position to permit adjustment 25 of the cam 35 relatively to the lever pin 34 to regulate the throw of the pawl 23. A screw 69 is threaded into a part of the arm 65 to strike against the framework 68 to limit the forward adjustment of the cam 35; and a 30 screw 70 is threaded through the arm 65 below the pivot 67 to bear against the framework 68, and to swivel said arm about said pivot and press the end of the screw 69 against the framework 68. The arm 61 is 35 sufficiently yielding to permit the vibration of the bar 59. The hub 66 is secured to the gudgeon 67 by means of a screw 71, so that the parts may be readily attached to and removed from the machine.

40. The side plates 29, 30 are suitably held together as by rods 72, and are secured by screws 73 to a bracket 74 detachably connected by thumb-screws 75 to the right hand end 4 of the platen frame, said bracket or arm 45 74 projecting from said end toward the opposite end of the platen frame and in rear of the platen. The auxiliary framework comprising the side plates 29, 30 is releasably connected by a pair of latches 76, one upon each 50 side plate, to the rod 77 which usually connects the ends of the platen frame and carries the usual paper guides; said plates 29, and 30 being slotted at 78 to fit down upon said rod.

Variations may be resorted to within the 55 scope of my invention, and portions of my improvements may be used without others.

Having thus described my invention, I claim:

1. In a typewriting machine having a rev- 60 oluble platen and line-space mechanism therefor, the combination with a spool-holder, of a feeding roll between said spool holder and the platen, a roll between the spool-holder and the platen to co-operate 65 with said feeding roll independently of the

platen to pull the paper ribbon from the spool, and a second roll co-operating with said feeding roll to pull said ribbon from the platen independently of the latter.

2. In a typewriting machine having a rev- 70 oluble platen and a line-space mechanism therefor, the combination with a spool-holder in rear of the platen, of a feeding roll between the spool-holder and the platen, a roll bearing up against the under side of said feeding roll to co-operate therewith independently of the platen to pull the paper ribbon from the spool, and a roll bearing down upon the top of said feeding roll to co-operate therewith to pull said ribbon from 80 the platen independently of the latter.

3. In a typewriting machine having a rev- 85 oluble platen and line-spacing mechanism therefor, the combination with a spool for carrying a ribbon of paper, of a milled hard feeding roll, releasable rolls of yielding material pressing against said feeding roll, one to pull the paper from the spool and the other to pull the paper from the platen, and means independent of the platen for rotating said 90 milled roll while the platen is stationary.

4. In a typewriting machine having a rev- 95 oluble platen and line-space mechanism therefor, the combination with a spool-holder, of a feeding roll between said spool-holder and the platen, a releasable roll co-operating with said feeding roll independently of the platen to pull the paper ribbon from the spool, and a second roll co-operating with said feeding roll to pull said ribbon from the 100 platen while the latter is motionless.

5. In a typewriting machine having a rev- 105 oluble platen and line-space mechanism therefor, the combination with a spool-holder, of a feeding roll between said spool-holder and the platen, a roll co-operating with said feeding roll independently of the platen to pull the paper ribbon from the spool, and a releasable roll co-operating with said feeding roll to pull said ribbon from the 110 platen independently of the latter.

6. In a typewriting machine having a rev- 115 oluble platen and line-space mechanism therefor, the combination with a spool-holder, of a feeding roll between said spool-holder and the platen, mechanism for intermittently advancing said feeding roll line by line while the platen is motionless, a finger-wheel for turning said feeding roll, and rolls pressing upon said feeding roll and releasable 120 therefrom independently of each other; one releasable roll for pulling the paper ribbon from the spool, and the other for pulling the ribbon from the platen.

7. In a typewriting machine having a rev- 125 oluble platen, a line-spacing mechanism therefor, and a frame whereon the platen is mounted, the combination of an auxiliary framework mounted upon a platen frame, and comprising a pair of side-plates, a spool- 130

holder, and a feeding roll mounted between said plates and supported thereby, spring-pressed bails hinged upon said plates, the latter being confined between the arms of the bails, and rolls pressing on opposite sides of said feeding-roll to co-operate therewith to pull the strip of paper from the spool and to pull the strip from the platen, said pressing rolls having axles extending through slots and said plates and carried upon said bail arms; and means to rotate said feeding roll to feed the strip while the platen is stationary.

8. In a typewriting machine having a revoluble platen, a line-spacing mechanism therefor, and a frame whereon the platen is mounted, the combination of an auxiliary framework mounted upon a platen frame, and comprising a pair of side-plates, a spool-holder, and a feeding roll mounted between said plates and supported thereby, bails hinged upon said plates, the latter being confined between the arms of the bails, and rolls pressing on opposite sides of said feeding roll to co-operate therewith to pull the strip of paper from the spool and to pull the strip from the platen, said pressing rolls having axles extending through slots and said plates and carried upon said bail arms, one of said bails mounted above and the other below said feeding-roll, the latter being provided with a finger-wheel, and a spring connecting said bails to cause both pressure rolls to bear against the feeding roll to permit the bails to move, to release the feeding rolls singly.

9. In a typewriting machine having a platen frame, a platen revolvably mounted therein, line spacing mechanism for the platen and a rod mounted upon said platen frame adjacent to the platen and extending along the same, the combination of a framework comprising a pair of connected side-plates, a bracket fixed to one end of the platen frame and extending inwardly from said end and fixed to one of the side-plates, said side-plates connected to said rod, a spool mounted detachably between said side-plates, rolls also mounted between said side-plates and disposed between the spool and the platen and co-operating to pull the paper ribbon from the spool and from the platen, and means to rotate said rolls to feed a paper strip from the spool and around the platen while the latter remains stationary.

10. In a typewriting machine having a revoluble platen and line-spacing mechanism therefor, the combination with a spool-holder, of means between the spool-holder and the platen and operable independently of the latter for pulling the paper ribbon from the spool and from the platen, and a brake for said spool.

11. In a typewriting machine having a revoluble platen and line-space mechanism therefor, the combination with a spool-

holder, of a feeding roll between said spool-holder and the platen and operable independently of the latter, a roll co-operating with said feeding roll to pull the paper ribbon from the spool, a second roll co-operating with said feeding roll to pull said ribbon from the platen, and a brake for the spool.

12. In a typewriting machine having a revoluble platen and line-space mechanism therefor, the combination with a spool-holder, of a feeding roll between said spool-holder and the platen and operable independently of the latter, a roll co-operating with said feeding roll to pull the paper ribbon from the spool, a second roll co-operating with said feeding roll to pull said ribbon from the platen, a brake for the spool, and means for silencing said brake.

13. In a typewriting machine having a revoluble platen and line-spacing mechanism therefor, the combination with a spool-holder and means operable independently of the platen for pulling the paper ribbon from the spool and from the platen, of a pivoted brake for said spool and a spring connected to said brake to hold it either against or away from the spool at will.

14. In a typewriting machine having a revoluble platen and line-spacing mechanism therefor, the combination with a spool-holder and means for pulling the paper ribbon from the spool and from the platen independently of the latter, of a pivoted brake for said spool and a spring connected to said brake to hold it either against or away from the spool at will; said brake being in the form of a bail extending along the spool and said spring being mounted to act on either side of the bail, to either press the bail against the spool or hold it away from the spool at will.

15. In a typewriting machine having a carriage, a platen mounted revolvably thereon, and line-spacing mechanism for the platen, the combination with auxiliary rolls for feeding paper relatively to the platen, and line-spacing mechanism independent of the platen and actuated by the movements of said carriage and co-operating with said auxiliary rolls, of means for silencing said line-spacing mechanism.

16. In a typewriting machine having a carriage, a platen revolvble thereon and a line-spacing mechanism for the platen, the combination with a spool-holder and rolls co-operating to pull a paper ribbon from the spool and from the platen, of an auxiliary line-spacing mechanism for said rolls including a rigid wheel and a pawl, and also including a pawl-actuator reciprocated by means of the movements of said carriage, and means for moving said pawl to an ineffective position.

17. In a typewriting machine having a carriage and platen mounted revolvably thereon and line-spacing mechanism for the platen,

the combination with a spool and auxiliary rolls for feeding paper from said spool around the stationary platen, of line-spacing mechanism actuated by the movements of said carriage and co-operating with said auxiliary rolls, a brake for said spool, and means for silencing said brake simultaneously with said auxiliary line spacing mechanism.

18. In a typewriting machine having a revoluble platen and line-spacing mechanism therefor, the combination with a spool-holder, of rolls between the spool-holder and the platen and co-operating with one another independently of the platen to pull the paper from the spool and from the platen; said spool detachable from the machine independently of said rolls; and means for rotating said rolls while the platen remains motionless.

19. In a typewriting machine having a platen frame, a platen revoluble thereon, and line-spacing mechanism for the platen, the combination with a spool-holder, of rolls, and means for causing the rolls to unwind a paper ribbon from the spool and pull it from the platen while the latter is motionless; said spool being mounted for detachment from the frame independently of said rolls.

20. In a typewriting machine having a carriage, a platen revoluble thereon, and line-spacing mechanism for the platen, the combination with a spool-holder, and means to unwind the spool and pull the paper from the platen, of a lever, means dependent upon the movement of the carriage for operating said lever, a slide connected to said lever, a pawl mounted upon said slide, and a ratchet wheel operated by said pawl and connected to said unwinding means.

21. In a typewriting machine having a carriage, a platen, and line-feeding mechanism for the platen, the combination with rolls co-operating to unwind a paper strip from a spool and pull a strip from the platen, of a pawl and ratchet upon said carriage for feeding the rolls, means for operating the pawl by reason of the movements of the carriage and including a cam mounted upon the framework, and means for adjusting the position of said cam, to regulate the throw of said pawl.

22. In a typewriting machine having a carriage, a platen, and line-feeding mechanism for the platen, the combination with rolls co-operating to unwind a paper strip from a spool and pull a strip from the platen, of a pawl and ratchet upon said carriage for feeding the rolls, means for operating the pawl by reason of the movements of the carriage and including a cam mounted upon the framework, and means for adjusting the position of said cam, a bar upon the framework extending along the carriage, an arm upon the upper end, on which one end of said bar is carried, said arm being pivotally mounted on its lower end upon the framework of the machine and screws to adjust and fix the position of said arm, thereby to adjust said cam to regulate the throw of said pawl.

23. In a typewriting machine having a carriage, a platen mounted thereon, line-spacing mechanism for the platen, and a rod extending along the platen, the combination of a strip-feeding mechanism mounted in an auxiliary framework which is detachably mounted upon said carriage, said strip-feeding mechanism including a line-feeding pawl and an actuator therefor, and a cam detachably mounted upon the framework of the machine in the path of said actuator, to operate the latter by reason of the movement of the carriage.

24. In a typewriting machine having a carriage, a platen mounted thereon, line-spacing mechanism for the platen, and a rod extending along the platen, the combination of a strip-feeding mechanism mounted in an auxiliary framework which is detachably mounted upon said carriage, said strip-feeding mechanism including a line-feeding pawl and an actuator therefor, and a cam detachably mounted upon the framework of the machine in the path of said actuator, to operate the latter by reason of the movement of the carriage; means being provided for effecting relative adjustment of said actuator, and said cam to regulate the throw of said pawl.

CARL F. LUNDEBERG.
